UNITED STATES PATENT OFFICE.

HENRY L. EBSEN, OF HOBOKEN, NEW JERSEY, ASSIGNOR TO JAMES REILLY REPAIR AND SUPPLY COMPANY, OF JERSEY CITY, NEW JERSEY, A CORPORATION OF NEW JERSEY.

DESIGN FOR AN INTERIOR FRAME FOR FILTERS.

SPECIFICATION forming part of Design No. 35,722, dated February 11, 1902.

Application filed January 2, 1902. Serial No. 88,251. Term of patent 14 years.

To all whom it may concern:

Be it known that I, HENRY L. EBSEN, a citizen of the United States, residing at Hoboken, in the county of Hudson and State of New Jersey, have invented and produced a new, useful, and original Design for an Interior Frame for Filters, of which the following is a specification, reference being had to the accompanying drawings, forming a part thereof, and in which—

Figure 1 is a side elevation of an interior frame for filters bearing and incorporating my design, and Fig. 2 is a section of same on the dotted line 2 of Fig. 1.

The leading feature of my design consists in the form and configuration of the interior frame, substantially as shown in the drawings.

The frame shown is intended for use in apparatus more especially applicable for filtering feed-water for steam-generators, the water passing through suitable filtering media and said frame on its way to the point of delivery.

In the drawings, A designates the interior frame, and said frame, as shown, is of elongated form and composed of the connected series of corresponding radial wings B, all of which lie within the outline of a circle and have the outer rounded ends C, whence the sides of said wings converge and connect with the adjacent sides of the adjacent wings on curved lines, as shown, there being an absence as far as possible of flat surfaces and angles in the configuration of the said frame. The entire surface of the frame A is perforated, as shown.

What I claim is—

The design for an interior frame for filters, substantially as shown and described.

Signed at New York, in the county and State of New York, this 28th day of December, 1901.

HENRY L. EBSEN.
